UNITED STATES PATENT OFFICE.

CARL WILHELM SÖDERBERG, OF CHRISTIANIA, NORWAY, ASSIGNOR TO DET NORSKE AKTIESELSKAB FOR ELEKTROKEMISK INDUSTRI, OF CHRISTIANIA, NORWAY, A BUSINESS ENTITY.

ELECTRODE HOLDER.

Application filed January 24, 1921. Serial No. 439,653.

To all whom it may concern:

Be it known that I, CARL WILHELM SÖDERBERG, a subject of the King of Norway, and a resident of Christiania, Kingdom of Norway, have invented certain new and useful Improvements in Electrode Holders, of which the following is a specification.

The invention forming the subject-matter of this application is especially designed for holding large electrodes such as are used in electric furnaces, and, while capable of use with such electrodes generally, has for its special purpose its use with electrodes of such class made and used in accordance with the disclosure of applications filed in the United States Patent Office by C. W. Söderberg on the 4th day of December 1917 (Sr. No. 205,416) and on the 8th day of September 1919 (Sr. No. 322,840), and the invention is here shown and described in connection with the electrode of the last named application. The electrodes described in the said two applications are built up outside of the furnace from time to time, as they are fed into the furnace, and at a rate determined by the consumption of the furnace ends thereof in use. The present holder is therefore designed with a view of firmly supporting the electrode between the feed intervals and having its hold on the electrode readily released to a limited and proper extent when it is desired to feed, to allow the electrode to slowly slide down under the control of the braking effect of the partially released holder. To this end the contact surface between the electrode and the holder is made large, this being also of value in decreasing the density of the heating current per square unit of the surface, which is fed to the electrode through the holder, and the parts are so arranged that the electrode is held by the friction between it and the holder, and not by interlocking projections on the holder and electrode. The latter construction would prevent control during feed.

For the purposes stated my invention consists in the construction, arrangement and combination of the several parts of which it is composed, as will be hereinafter more fully described and claimed.

Referring to the accompanying drawings in which corresponding parts are designated by corresponding marks of reference.

Figure 1 is a vertical section through a furnace equipped with this invention.

Figure 2 is a vertical section taken at right angles thereto.

Figures 3 and 4 are horizontal sections through an electrode and a holder, the latter being constructed in accordance with this invention and the sections being taken on lines III—III and IV—IV, respectively, of Figure 5.

Figure 5 is an elevation of such an electrode and holder, parts being broken away for purposes of illustration.

Figure 6 is a horizontal section taken on lines VI—VI of Figure 5.

Figure 7 is a side elevation of one of the jaws of the holder, showing the attachment of the strap and conducting bands.

Figure 8 is a vertical section of another modification of the holder.

Figure 9 is a horizontal section taken on lines VII—VII of Figure 8.

As shown in the drawings the furnace 1 has erected above it, on a framed superstructure 2, a housing 3, while the electrodes 4 project into the furnace. The electrodes 80 are of the type disclosed in the Söderberg application, Sr. No. 322,840, above referred to, that is, are shown as including a metallic sectional mantle 4^a surrounding the carbonaceous core of the electrode. In the use 85 of such electrodes a mantle section is added to the upper end of the electrode, from time to time, as the electrode is fed to the furnace and such mantle section is packed with raw electrode material which is baked after being 90 added to the electrode, the baking being due to the heat of the furnace, with or without the aid of a preliminary partial baking by the heat generated by the passage of the current through the electrode. The packing of 95 the raw electrode mass into the mantles is conveniently done in the housing 3, which protects the operators engaged in the work from the heat and fumes arising from the furnace. A description of such an electrode 100 and of the formation of the same is shown in the "Iron Age" New York, April 22, 1920, on pages 1171—1172—1173.

Referring to Figures 1—7 each holder is suspended on a superstructure by a tackle 5 105 which directly supports a platform 6 surrounding the corresponding electrode above the furnace, and from which platform the

remaining parts of the holder are hung by bolts 7, the lower ends of which are connected to the conducting straps 8 8^a, also surrounding the electrode. In the drawings the 5 conducting straps are shown as forming polygonal closed rings and to each of their sides is connected the upper end of a clutch jaw 9 by a clutch jaw hanger strap 9^a. The lower end of the jaws is surrounded by a 10 clamp ring 10, the jaws having exterior shoulders 9^b on their lower ends to serve as a support for the ring. The ring opposite each jaw receives a bushing 11^a which is tapped to receive a clamp screw 11, the end 15 of which bears on such jaw and determines the radial position thereof.

Each part of the rings and each of the jaws are provided with suitable passageways therethrough. One of the jaws is connected with the water induction pipe 12, while an adjacent jaw is connected with the water eduction pipe 12^a. The circuit for the water circulation through the jaws is completed by the pipes 13 connecting adjacent 25 jaws and extending upwardly along the outside of the electrode, whereby sufficient freedom of movement is given to the adjacent jaws without straining the connection between them. A water induction pipe 14 is 30 connected with one end of one of the ring sections and the water eduction pipe 15 with the adjacent end of the other section. Thus injury to the holder from heat is prevented and the temperature of the holder is reduced.

In order to provide a proper and equal current feed into the several jaws a supplemental conducting band 8 encircles the electrode immediately below the band 8 and both 40 bands have both of their ends connected to the clamp 16 on the feeding conductor 16^a, 16^b. The band 8 is electrically connected with all of the jaws, while the band 8^a is only connected with the jaws opposite to and remote from the ends of such band, the band 45 being either not mechanically connected with, or being insulated by the strips 8^b from the other jaws. By giving the supplemental band higher conductance than the band 8 the 50 current flow into the several jaws will be thus equalized.

The Figures 8 and 9 differ from those described above in that the clamp ring 10 also serves as a conducting band and is directly 55 connected to the feeding conductor. It is suspended on the superstructure by the tackle 5. Each jaw 9 is provided with a shoulder 17 bearing on the clamp ring and being supported thereby.

60 With the parts thus constructed, when it is desired to feed an electrode, one or more of the screws 11 may be backed out slightly, reducing the pressure exerted by the jaws on the electrode, until the latter slides downwardly in the holder at a rate capable of be-

ing controlled by the pressure left upon it by the holder. In practice it has been found that under normal conditions an electrode 32 inches in diameter and 15 feet in length may be so fed by backing out not 70 more than two of the screws, and that it is not necessary to shut off the current in so doing.

It will be noted that the specific construction shown herein provides a plurality (in 75 the specific instance 3 sets) of clamping jaws, and that the frictional resistance offered to the descent of the electrode is the sum total of the frictional resistance due to the several pairs. Thus by releasing a jaw of one 80 of the pairs the total resistance may be reduced by an amount to the resistance of such pair. If the resistance of the remaining pairs is of proper value (which can be effected by placing proper pressure on the jaws of 85 such other pairs), the electrode will feed under the braking effect of the remaining pairs of jaws. Thus by using a plurality of pairs of jaws a predetermined braking effect does not require that the released jaw be 90 released by any definite amount, and this facilitates control of feeding.

What I claim as new and desire to secure by Letters Patent of the United States is:

1. In an electrode holder the combination 95 of a plurality of conductor elements and means for permitting a limited independent outward movement of said elements, whereby a controlled slippage of the electrode is provided for.

2. In an electrode holder the combination of jaws, a ring surrounding the jaws and means carried by the ring for permitting a limited independent outward movement of the several jaws, whereby a controlled slippage of the electrode is provided for. 105

3. In an electrode holder the combination of a plurality of water cooled conductor elements and means for permitting a limited independent outward movement of said elements, whereby one or more of the said conductor elements may be loosened and a controlled slippage of the electrode is provided for. 110

4. In an electrode holder, the combination of a plurality of opposite sets of jaws, a ring surrounding the jaws, and means for permitting a limited independent outward movement of a jaw of one or more of the sets of jaws, whereby a controlled slippage of the 115 electrode is provided for.

5. In an electrode holder the combination of a watercooled ring, a plurality of watercooled conductor elements enclosed by the ring and severally connected therewith by belts, whereby one or more of the said conductor elements may be loosened and a controlled slippage of the electrode in the holder is provided for. 125

6. In an electrode holder, the combination 130

of jaws, a ring connecting the upper ends of the jaws, a ring surrounding the lower ends of the jaws, and means carried by the ring for permitting a limited independent outward movement of the several jaws, whereby a controlled slippage of the electrode is provided for.

7. In an electrode holder, the combination of a plurality of opposite sets of jaws, a ring surrounding the lower ends of the jaws, and means carried by the ring for permitting a limited independent outward movement of a jaw of one or more of the sets of jaws, whereby a controlled slippage of the electrode is provided for.

8. In an electrode holder, the combination of jaws, a ring connecting the upper ends of the jaws, a ring surrounding the lower ends of the jaws, and means carried by the ring for permitting a limited independent outward movement of the several jaws, whereby a controlled slippage of the electrode is provided for, and means for causing a water circulation through the jaws and clamping ring.

9. In an electrode holder, the combination with a current conducting ring, a plurality of jaws connected at their upper ends to the ring and having exterior shoulders on their lower ends, a clamping ring encircling the jaws and resting on the shoulders thereon, means carried by the clamping ring for determining the radial position of the jaws independently of each other, and means for supporting the clamping ring and thus the other parts of the holder.

10. In an electrode holder the combination

with gripping jaws of current distributing means for equalizing the feed of the current therethrough to the electrode.

40

11. In an electrode holder the combination with gripping jaws of a plurality of current distributing means for equalizing the feed of the current therethrough to the electrode.

45

12. In an electrode holder the combination of gripping jaws, a plurality of current distributing rings and selected connections between the rings and the jaws whereby the feed of the current to the electrode through the jaws is equalized.

50

13. In an electrode holder the combination of gripping jaws, a ring surrounding the jaws, means carried by the ring for permitting a limited independent outward movement of the several jaws, whereby a controlled slippage of the electrode is provided for, and current distributing means for equalizing the feed of the current through the jaws to the electrode.

55

14. In an electrode holder the combination of gripping jaws, a ring surrounding the jaws, means carried by the ring for permitting a limited independent outward movement of the several jaws, whereby a controlled slippage of electrode is provided for, a plurality of current distributing means, and selected connections between the distributing rings and the jaws whereby the feed of the current through the jaws to the electrode is equalized.

60

Signed at Christiania, Norway, this 31 day of December 1920.

CARL WILHELM SÖDERBERG.
